UNITED STATES PATENT OFFICE

134,284

DESIGN FOR A SLIPPER

Alexander H. Bailey, Darby, Pa.

Application September 18, 1942, Serial No. 108,271

Term of patent 14 years

To all whom it may concern:

Be it known that I, Alexander H. Bailey, a citizen of the United States, residing in Darby, county of Delaware, State of Pennsylvania, have invented a new, original, and ornamental Design for Slippers, of which the following is a specification, reference being had to the accompanying drawing, which forms a part thereof.

Fig. 1 is a plan view of a slipper showing my new design.

Fig. 2 is a side elevational view of the same, slightly in perspective.

I claim:

The ornamental design for a slipper, as shown.

ALEXANDER H. BAILEY.
